THREAD-ROLLING MACHINE.

No. 849,630.

Specification of Letters Patent.

Patented April 9, 1907.

Application filed February 20, 1906. Serial No. 301,979.

To all whom it may concern:

Be it known that we, GEORGE B. LAMB, DAVID C. GRIGGS, and ROY H. SMITH, citizens of the United States, residing at Waterbury, in the county of New Haven and State of Connecticut, have invented certain new and useful Improvements in Thread-Rolling Machines, of which the following is a specification, reference being had therein to the accompanying drawings.

Our invention relates to new and useful improvements in thread-rolling machines, and has for its object, among other things, to apply an improved hopper mechanism which will be positively operated, to assure the feeding of a single blank from the hopper to the dies at each successive stroke of the slide, to provide means for automatically holding the blank square with the dies until the same have engaged it sufficiently to assure the thread being rolled straight thereon, and means for knocking the threaded blank from the die after the same has been threaded, if perchance it should hang thereon.

To these and other ends our invention consists in the thread-rolling machine having certain details of construction and combinations of parts, as will be hereinafter described, and more particularly pointed out in the claims.

Referring to the drawings, in which like numerals of reference designate like parts in the several figures, Figure 1 is a plan view of our improved thread-rolling machine complete. Fig. 2 is a front elevation thereof. Fig. 3 is a sectional elevation of a portion of the mechanism, taken upon line A B of Fig. 2. Fig. 4 is an enlarged fragmentary elevation of the hopper-blade. Fig. 5 is a sectional view of the chute, taken upon line C D of Fig. 3. Fig. 6 is a fragmentary elevation of the adjustable blank-buffer. Fig. 7 is a fragmentary plan view of the pusher and cut-off slides. Fig. 8 is a front elevation thereof. Fig. 9 is a sectional view thereof upon line E F of Fig. 7. Fig. 10 is an elevation of a portion of the knock-off mechanism. Fig. 11 is a front elevation of a portion of the mechanism for alining the blanks, and Fig. 12 is an end elevation thereof.

In the practice of our invention we provide a bed 1, which is supported upon a suitable

pedestal 2. Movable mounted in this bed beneath the cap 7 is the slide 3, within which the movable die 4 is held by means of the clamp 5 and cap 6. A longitudinal movement is imparted to this slide through the crank-disk 8, connection 9 and gear 10 having an operative engagement with said crank-disk. The gear 10 is rotated through a pulley 12, fixed upon a shaft 13, rotatable in the bed 1 and the pinion 14, which meshes into the gear 10.

The fixed die is designated 15 and is held in a die-block 16 by the clamp 17. The die-block 16 is adjustably secured to the bed by any of the means common to the art and which do not constitute any part of the present invention.

The mechanism for automatically feeding the blanks to the dies comprises a hopper 18, that is secured to a plate 19, that is vertically adjustable upon a plate 20, integral with the journal-bracket 21, within which is rotatable the shaft 22, having the pinion 23 thereon, which meshes into and drives a pinion 24 upon a stud 25. Upon this same stud and rotatable with the pinion 24 is a pinion 26, which meshes into and drives a gear 27, having a roll 28 mounted upon one side thereof.

Pivoted to an arm 29, integral with a portion of the hopper 18, is the blade 30, having a tongue 40 upon its bottom edge that is movable in the path of rotation of the roll 28. The blade 30 is provided with a recess 31, and removably secured to the inner faces thereof at the upper edge are the filler-plates 32. Plates of varying thicknesses are used to accommodate blanks of different diameters. Leading from the hopper is a chute to conduct the blanks from the hopper to the dies, which chute comprises two parallel plates 33 and 34, having an open space therebetween of substantially the same width as the diameter of the blank. The plate 33 is secured to an arm 35 upon the hopper 18, with a filler-plate 36 between said plate and said arm. The width of the space between the plates 33 and 34 is varied by applying filler-blocks 37 of different thicknesses.

Supported above the top of the chute by adjustable plates 38 is a cover 39, (see Fig. 5,) leaving an open space therebetween of sufficient height to permit the head of the blanks

to pass thereunder, at the same time preventing the blanks from piling one on top of the other and assuring an orderly arrangement of the blanks within the chute.

5 In Fig. 3 the blade 30 is shown in its up position with the top edge thereof substantially parallel with and forming an extension of the top of the chute, so that the blanks therein slide out of said blade into said chute by 10 gravity. When the roll 28 is moved from its up to its down position, the blade drops by gravity, and at the next upward stroke some of the blanks are lifted out of the hopper by the blade and escape therefrom when the 15 blade is in its up position, as previously described. This chute is supported at its outer end by a plate 41, that permits of a limited adjustment of the chute in relation thereto.

Heretofore the hopper mechanism for 20 accomplishing the purposes herein described have always been driven by a belt, rope, or other similar mechanism, it being designed that the belt should slip if perchance any of the blanks should catch or the mechanism 25 become clogged. It has been demonstrated that this method of driving a hopper mechanism is defective, because the belt after a time becomes permeated with oil and has a tendency to slip upon the pulley irrespective 30 of whether the mechanism is clogged or not. To overcome this objection, we provide means whereby the hopper mechanism is positively driven by connecting some of the parts frictionally, which shall be sufficient to insure its 35 continuous rotation while all of the mechanisms are operating smoothly, but not sufficient, however, to prevent its slipping if the parts should become clogged or for other reasons the blanks should interfere with the 40 proper operation of the parts. This mechanism comprises a shaft 42, having a pinion 51 thereon, which is rotatably mounted in brackets 43 and 44, fixed to the bed 1 and rotated through a pinion 45, fixed upon said shaft 45 and meshing into the pinion 14. Upon the shaft 22 is a bevel-gear 46, which meshes into the pinion 51 and is frictionally secured by the nut 47 between the fiber washers 43 and 50, the first of said washers lying against 50 the collar 49 on said shaft. In operation if for any reason blanks should become clogged or the blade work improperly the gear 46 will rotate about the shaft 22 without imparting movement thereto, while at other times the friction is sufficient to rotate said shaft 55 with said gear.

In the cap 6 a buffer 51 is adjustably secured to accommodate blanks of various diameters, the adjustment being obtained by 60 the engagement of the pointed end of the screw 52 with the pointed end of the shank 53. A screw 54, which impinges against said shank, secures said buffer in its adjusted positions. This buffer is connected with said 65 slide, so that at one extreme end of its stroke

the buffer is directly opposite the chute, and the blanks as they pass therefrom engage said buffer, which determines their proper relative position with the dies.

In the general operation of our thread-rolling machine the blanks are conveyed from the hopper to the dies through the chute, thence between the movable and fixed dies by the action of the slide 3, and while passing between the dies the thread is rolled 70 thereon. In the thread-rolling machines common to the art it has been difficult heretofore to properly present the blanks to the dies, and if not properly engaged by the dies an imperfect thread results. We have 75 designed means to overcome this objection and to assure the proper alinement of the blank in reference to the dies not only as it passes out of the chute, but until the dies have had an opportunity to engage it a sufficient 80 length of time to prevent it afterward shifting its relative position between the dies. This means comprises a slide 55, which is movably mounted within a pan-block 56, that is adjustably secured upon the top of 85 the bed by the screws 57 and 58 and having a finger 59 affixed thereto, the front end of which is of slightly less width than the space between the faces of the two dies. This slide is operated from a cam 60, fixed on a shaft 90 11, having the disk 8 thereon, lever 61, which is fixed upon the end of a shaft 62, an arm 63, adjustably secured to said shaft and slotted at its outer end, with the side 64 thereof elongated, and a block 65, movably secured to the 95 slide 55 by a pin 66. Rotation of the cam 60 imparts a rocking movement to the arm 63 and a longitudinal movement to the slide 55. With the arm 63 having the elongated finger 64 convenient means are provided for 100 the readily assembling or removal of the slide 55 to accomplish either result, it being simply necessary to shift the position of the arm 63 to that shown by broken lines in Fig. 2, when the slide may be inserted or withdrawn from the block 56, as desired. 105

Upon the slide 3 is a bracket 67, which is adjustably secured thereto by the bolts 68. Movably secured within said bracket by the cap 69 is a slide 70, having fixed thereon a 110 stop-block 72 and a finger 71, the forward end of which is substantially the same thickness as that of the finger 59. The slide 70 is moved in one direction by a spring 73, which is connected at one end to the spring-pin 74 and at the other end to a post 75, fixed to the cap 69. Mounted within the block 56 adjacent to the slide 55 is a cut-off slide 76, having a finger-plate 77 secured to its front end and a stop-block 78 adjacent to its rear end. A pawl 79 is pivotally connected with the slide 55 and normally held in its up position by a spring 80. The slide 76 is moved in one direction by the spring 81, 115 that is fixed between the posts 82 and 83, 120

and in the opposite direction by the engagement of the pawl 79 with the notch 84 in said slide, a bumper-pin 85 being fixed in the path of said pawl so as to trip the same at the proper time. As the return movement of the slide 3 is about completed the slide 55, which moves rearwardly therewith, brings the arm of the pawl 79 into engagement with the bumper 85, releasing the same from the notch 84 in the cut-off slide 76. The spring 81 then actuates the cut-off slide, and the finger upon the plate 77 passes between the first and second blanks in the chute, forcing the first blank out of said chute and into a position between the ends of the fingers 59 and 71. This cut-off slide prevents the feeding of more than one blank at a time into the dies, and in addition by its engagement with the blanks agitates the column of blanks in the chute and keeps them in order. During the return movement of the slide 3 as above described the bracket 67, carrying the slide 70 therein, moves rearwardly therewith until the stop-block 72 engages the projecting edge of the die 15 (see Fig. 1) and limits its further movement. This stop-block is adjusted so that at the extreme end of the stroke of the slide 3 the front end of the finger 71 will be flush with the edge of the blank-chute. Simultaneously with the escape of the blank from the chute the slide 55 is actuated and the finger 59 engages the blank and holds it positively in a vertical position between the opposing ends of the finger 59 and said finger 71. The blank is thus held until the dies engage the same and until the blank has made at least one rotation therebetween, when the threads rolled thereon will be sufficient to prevent the blank from shifting out of alignment with the dies. It will be remembered that the finger 71 is movably connected with the slide 3, but during the first part of the movement of said slide the finger remains substantially stationary, except as it is moved by the blank being threaded, the spring 73 having a tendency to hold it in its forward position. After the slide 3 has moved a sufficient distance to permit the engagement of the end of the slide 70 with the cap 6 the finger 71 is withdrawn with the slide from between the dies. In brief, during the first portion of the thread-rolling operation the finger 71 recedes only at the same speed as the movement of the blank, which is less than that of the slide 3, but during the latter part of the thread-forming operation the finger 71 moves at the same speed as said slide and is drawn away from the blank.

Frequently after being rolled the blanks have a tendency to hold onto the dies, thereby causing the thread to become stripped or else injuring and destroying the dies. To overcome this difficulty and to assure the leaving of the dies by the blanks, we provide a knock-off which consists of a holder 86,

which is pivotally connected with the slide 3 by the screw 87 and having the roll 88 rotatably mounted thereon and carrying a laterally-projecting knock-off finger 89. During the movement of the slide 3 the roll 88 engages the cam 90, which is fixed to the cap 7, and just before the completion of the stroke of the slide 3 the engagement of the roll 88 with the arm 90 swings the holder 86, so that the finger 89 assumes the position shown by dotted lines 91 in Fig. 1, the fingers then being substantially parallel with the end of the die 4, and after the die 4 has passed the end of the die 15 the cam 90 actuates the finger 91, which then assumes the position shown by broken lines 92, which is over the edge of the die, and while assuming this position knocks off any blank which has a tendency to hang or adhere to the die.

The mechanism for supplying oil to the dies comprises an oil-reservoir, a pump, (not shown,) which is driven by a belt 93, and a pipe 94, connected with said pump and terminating in a nozzle end 95, that lies above the dies and has a plurality of perforations (not shown) in the bottom thereof. The oil is forced through the pipe 94 by the pump and escapes through the nozzle-perforations and drops in streams onto the dies and finger 71. The action of the moving die through the streams of oil cleanses and lubricates it, while in the stationary die the finger 71, which is thoroughly wet with oil, moves in front of said die and wipes off the face thereof, thus distributing the oil uniformly over the whole face. After leaving the dies the oil is reconducted by any convenient means to the reservoir.

There are minor changes and alterations that can be made within our invention, and we would therefore have it understood that we do not limit ourselves to the exact construction herein shown and described, but claim all that falls fairly within the spirit and scope of our invention.

Having described our invention, what we claim as new, and desire to secure by Letters Patent, is—

1. In a thread-rolling machine, the combination with a reciprocating slide; of a threading-die connected therewith; a fixed die; a finger connected with said slide and having an independent endwise movement thereon; and a second finger movable toward and away from said first-mentioned finger, said first-mentioned finger being operated by said second finger during a portion of its stroke by the blank for a portion of its stroke and by the said slide for another portion of its stroke.

2. In a thread-rolling machine, the combination with a slide; of a threading-die connected therewith; a fixed die; a pair of fingers operative between said dies; means for moving one of said fingers at varying speeds

during the same stroke; and means for reciprocating the other of said fingers toward and away from the first-mentioned finger during the same stroke.

- 5 3. In a thread-rolling machine, the combination with a reciprocating slide; of a threading-die connected therewith; a finger connected with said slide and having an independent movement therewith; a fixed die; a second finger; said fingers being arranged so as to grasp a blank between the opposing ends thereof when the movable die is in its retracted position; means for imparting movement to said second finger so as to present the blank between said dies; and move said first finger by the time the end of the movable die is opposite the end of said fixed die; means for withdrawing said second finger after said dies have engaged said blank; and means connected with said slide for engaging said first finger and moving the same therewith after the blank has in part pushed said finger in advance of itself between said dies.
- 25 4. In a thread-rolling machine, the combination with a slide; of a movable die; a fixed die; a knock-off mechanism, comprising a knock-off arm pivotally connected with said slide; and cam mechanism fixed in the path
- 30 of said knock-off arm for moving the same on its pivot-mounting and thereby sweeping

over the ends of said dies after the thread-rolling operation.

5. In a thread-rolling machine, the combination with a slide; of a die connected therewith; a knock-off arm pivotally mounted on said slide adjacent to the rear end of said die and carrying a projecting part; and a cam fixed in the path of said projecting part to actuate said knock-off arm.

40 6. In a thread-rolling machine, the combination with a fixed die; a slide; a die fixed to said slide; a feed-chute; and an adjustable buffer fixed to said slide adjacent to the end of said movable die; and arranged to be 45 opposite said feed-chute at the completion of each stroke of said slide.

7. The combination with a hopper-blade 30 having a recess 31 in the upper edge thereof; of the filling-plates 32 secured to the inner walls of said recess, said plates being 50 opposite to each other with their top edges substantially flush with the upper edge of said blade.

In testimony whereof we affix our signatures in presence of two witnesses.

GEORGE B. LAMB.
DAVID C. GRIGGS.
ROY H. SMITH.
